UNITED STATES PATENT OFFICE

WASHINGTON MAYNARD, OF ASSUMPTION, ILLINOIS.

GRAFTING IMPLEMENT.

SPECIFICATION forming part of Letters Patent No. 351,879, dated November 2, 1886.

Application filed September 3, 1886. Serial No. 212,636. (No model.)

To all whom it may concern:

Be it known that I, WASHINGTON MAYNARD, a citizen of the United States, residing at Assumption, in the county of Christian and State of Illinois, have invented certain new and useful Improvements in Grafting Implements; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 The invention will first be described in connection with the drawings and then clearly pointed out in the claim.

Figure 1 of the drawings is a perspective view of my device; Fig. 2, a vertical section on line $\alpha\alpha$ of Fig. 1; Fig. 3, a detail view in longitudinal section, and Fig. 4 a partial view showing the plunger-knives and guard-plate.

20 In the drawings, A represents the bed of my machine, and B B two oppositely-grooved uprights, between which reciprocates a plunger, C. On the back of this plunger is a stud, e, under which extends the front free end of a plate-spring, D, whose rear end may be fastened to a bed-block, E.

25 On the lower end of the plunger C are arranged three knives, F G H, so that they will make the three cuts f g h. (Shown in Fig. 3 of the drawings.) The knife F on the right hand cuts the shoulder f, the front knife, G,

makes the diagonal cut g, and the left-hand 35 knife, H, makes the end cut, h, thus giving a definite length to the joint. The knives may be secured under shoulders of the plunger, as well as the guard-plate I, by screws or screw-clamped plates, or in any other suitable manner.

30 J J are right-angled stop-plates, made adjustable in grooves of the block K by set-screws L L, so as to give the depth of shoulder and thickness of end. M is a lever for holding scion and root securely in the desired position.

The machine may be fastened on a table and worked with a treadle by the foot, or by any preferred power or mechanism, the operator 50 being seated in front thereof.

Having thus described all that is necessary to a full understanding of my invention, what I claim as new is—

55 In a machine for cutting root-grafts, the reciprocating plunger C, having the shoulder-knife F, the diagonal cutter G, and the end cutter, H, in combination with the guard-plate I, stop-plates J J, and lever M, all arranged substantially as and for the purpose 60 set forth.

In testimony whereof I affix my signature in presence of two witnesses.

WASHINGTON MAYNARD.

Witnesses:

M. L. BARNETT,
ISAAC CAMPBELL.
